CLAIM

I claim the ornamental design for a refuse container lid, as shown and described.

DESCRIPTION

FIG. 1 is a top, front perspective view of a refuse container lid showing my new design, shown in an open position; FIG. 2 is a top, front perspective view thereof, shown in a closed position;

FIG. 3 is a front view thereof;

FIG. 4 is a rear view thereof;

FIG. 5 is a left side view thereof; shown in an open position;

FIG. 6 is a right side view thereof;

FIG. 7 is a top view thereof; and,

FIG. 8 is a bottom view thereof.

The broken lines show portions of the refuse container lid which form no part of the claimed design.
